US00D603519S

(12) **United States Design Patent**
Tavidian

(10) **Patent No.:** **US D603,519 S**
(45) **Date of Patent:** **** Nov. 3, 2009**

(54) **ELECTROSTIMULATOR OF VENOUS SYSTEM**

(75) Inventor: **Thierry Tavidian, Paris (FR)**

(73) Assignee: **AD REM Technology, Paris (FR)**

(**) Term: **14 Years**

(21) Appl. No.: **29/284,700**

(22) Filed: **Sep. 13, 2007**

(51) **LOC (9) Cl. 24-01**

(52) **U.S. Cl. D24/186**

(58) **Field of Classification Search** D24/107, D24/158, 164, 167, 170, 186-187, 231; 600/300, 600/301, 368, 372, 481, 529, 544, 554, 561, 600/249; D8/367, 373; D23/210; 422/44; 601/12; 607/21

(57) **CLAIM**

The ornamental design for a electrostimulator of venous system, as shown.

DESCRIPTION

FIG. 1 is a perspective view of a electrostimulator of venous system showing my new design;

FIG. 2 is a front view thereof;

FIG. 3 is a back view thereof;

FIG. 4 is a left elevational thereof;

FIG. 5 is a right side view thereof;

FIG. 6 is a top plan view thereof; and,

FIG. 7 is a bottom plan view thereof.
